UNITED STATES PATENT OFFICE.

WILLIAM A. BOLE, OF PITTSBURGH, PENNSYLVANIA.

WORKING CYLINDER OF INTERNAL-COMBUSTION ENGINES.

1,187,492.

Specification of Letters Patent. Patented June 20, 1916.

Application filed March 22, 1910. Serial No. 551,006.

To all whom it may concern:

Be it known that I, WILLIAM A. BOLE, a citizen of the United States, and a resident of Pittsburgh, in the county of Allegheny 5 and State of Pennsylvania, have made a new and useful invention in Working Cylinders of Internal-Combustion Engines, of which the following is a specification.

This invention relates to engine cylinders 10 and more particularly to the cylinders of internal combustion engines of the water cooled type.

It has become necessary under certain conditions to make the cylinders of large gas 15 engines out of steel. These may be forged but are preferably cast. As all gas engines of the larger sizes are necessarily water cooled it is necessary to provide the cylinders with a water jacket and this, in the way the 20 cylinders have heretofore been made, has very materially complicated their manufacture.

When the cylinders are made of cast iron it is not impossible to core the casting in 25 such a manner that the jacket shell is a part of the cylinder casting. This of course is impossible in making forged cylinders and has proven very difficult in making cast steel cylinders.

30 I am aware that various attempts have been made to mechanically secure the jacket shells to the cylinders by utilizing bolts or screws and various kinds of packing, but so far as I am aware none of these schemes 35 have proved satisfactory.

An object of this invention is to produce 35 a jacketed cylinder which may be forged from steel or cast either of steel or gray iron.

40 A further object has been to provide a cylinder that may have its outer surface machined in order to provide a uniform wall thickness and has a jacket shell united to the cylinder without the means of bolts or 45 screws or packing.

These and other objects I accomplish by the means described in the specification and illustrated in the single sheet of drawing accompanying same.

50 It will be understood that this invention is applicable to a great variety of designs

of engine cylinder whether for horizontal or vertical engines, or whether single or double acting. In the drawing I have illustrated a cylinder for a horizontal double acting engine. The cylinder 2 is provided with inlet ports 3—3 and exhaust ports 4—4. The cylinder is preferably of cast steel and is so formed that the outer surface 5 may be rough machined in order to secure a uniform cylinder wall thickness. The outer surfaces of the end flanges 6—6 are preferably turned off so as to be concentric with the cylinder bore.

A sheet steel shell 7, made up of any desired number of pieces united together is 65 weld united to the cylinder body which is preferably provided with flanges 8 and 9 of substantially the same thickness as the shell 8, so as to facilitate the welding process in that the flanges can be heated at the same 70 speed as the shell.

One or more hand holes 10 may be provided in the shell so that the interior of the water jacket formed by the shell may be inspected and cleaned out. The steel shell is 75 preferably corrugated in order to allow for the expansions and contractions due to temperature changes encountered in the operation of the engine. The jacket shell may be weld united to the cylinder body by any suitable welding process such as acetylene or electric welding, the acetylene welding however being preferred.

Having now described my invention, what I claim is:

1. A steel cylinder having a welding flange integrally formed thereon and of substantially the same heat conducting capacity as the metal sheet secured thereto, and a metal sheet autogenously secured to said flange and 90 forming with the exterior surface of the cylinder a passage located outside of the cylinder.

2. A steel cylinder having welding flanges integrally formed thereon, a sheet steel shell 95 surrounding said cylinder and autogenously secured to said flanges, said flanges being so formed that the shell engaging portions thereof have substantially the same heat conducting capacity as the metal shell secured thereto.

3. A steel cylinder having a welding flange

2
cast integrally therewith and so formed as to be of substantially the same heat conducting capacity as the metal sheet secured thereto, and a metal sheet autogenously secured to said flange and forming with the exterior surface of the cylinder a passage located on the outside of the cylinder.

In testimony whereof, I have hereunto subscribed my name this 10th day of March, 1910.

WILLIAM A. BOLE.
